UNITED STATES PATENT OFFICE

2,134,339

DEVICE FOR CONDITIONING AND SHARPENING IMPLEMENTS

Robert T. McDonald, Hornell, N. Y., assignor of
one-half to Eugene E. Grimm, Franklin, Pa.

Application September 25, 1935, Serial No. 42,087

3 Claims. (Cl. 51—204)

This invention relates to devices for conditioning or sharpening implements and it has particular relation to an abrasive conditioning device which is adapted to be used either as a surface conditioner for knife sharpeners or as a sharpening tool for blades, or the like.

One object of the invention is to provide an improved surface conditioner for metal knife sharpeners.

10 Another object of the invention is to provide an improved surface conditioner for knife sharpeners which is also so constructed as to serve as a sharpener for metal blades.

The invention is exemplified in an arrangement 15 of a plurality of abrasive sections surrounding a central opening through which a blade sharpener can be inserted and reciprocated, or oscillated, or otherwise frictionally forced against the inner surfaces of the sections to recondition or roughen 20 the sharpener surface. The sections are resiliently held together in assembled relation and are of such length as to be adapted for manual operation by an operator holding the conditioner in one hand and the sharpener in the other. The 25 opposed faces of the sections are provided with beveled converging surface portions which are adapted to receive an edge of a blade for sharpening the latter by proper manipulation thereof.

In the drawing:

30 Fig. 1 is a perspective of an abrasive conditioner in an operative position in connection with a sharpening tool;

Fig. 2 is a perspective of the principal elements of the improved device and shown in disassembled relation;

Fig. 3 is an end elevation of the conditioner and illustrating a different form of device for maintaining the elements thereof in assembled relation;

40 Fig. 4 is a perspective of the conditioner as it is used for sharpening a knife; and

Fig. 5 is a cross section taken substantially along the line V—V of Fig. 4.

In practicing the invention a conditioner 10 45 is constructed of complementary sections 12 preferably oblong in form and they are provided with normally abutting surfaces 15 which can be held in proper non-shifting, but in separating, relation by means of dowels 16 provided on one face 50 15 for loosely fitting into openings 17 in the other face. Opposed channels 18 are formed centrally along the abutting faces of the sections 12, and in the assembled relation of the sections these channels constitute an axial passage extending 55 entirely through the conditioner 10.

Opposed faces of the sections 12 adjacent one end of the conditioner are beveled, as indicated at 19, and when the faces 15 are in abutting relation to each other the opposed beveled portions of the sections define cusp-shaped crevices 20 5 (Fig. 5), wherein the inner portions of the surfaces defining them converge into substantial contact with each other.

In order to maintain the sections 12 in assembled relation the outer circumferential section 10 surfaces are grooved, as indicated at 22, to form a seat for a resilient band 23 encircling the conditioner and normally under tension. This band can be in the form of endless elastic material, such as rubber, or it can be in the form of a 15 resilient metal strip, or ring 24 (Fig. 3). When a rubber band is used the dowels 16 prevent longitudinal relative shifting movement of the sections in axial directions. When a metal band is employed the dowels can be dispensed with because 20 the band seated in the groove portions 22 prevent such shifting of the sections.

In Fig. 3 the resilient metal band 24 is sinuous or corrugated and endless. The corrugations 25 of the band 24 permit the band to be expanded in 25 order that it can be slipped over the sections and seated in the grooved portions 22 thereof. The band can also be in the form of a split ring or band 26 having a bent portion or lug 27 that is normally positioned in one of the crevices 20 30 to prevent circumferential shifting of the ring, and its end portions are outwardly turned slightly to form finger pieces 28 for the purpose of facilitating the manual manipulation thereof. Since 35 the end portions 28 are disposed adjacent the crevice 20, the operator's fingers can more conveniently engage them for removal of the ring, when such operations are desired.

The sections 12 are composed of coarse grained abrasive material, such as carborundum, and can 40 be cast, moulded, or otherwise shaped into the form shown.

A sharpening tool 30, for example, the kind commonly used in sharpening knives is inserted through the axial opening formed by the channels 18 and the spreading of the sections is resisted by the resilient band as the tool is inserted. By holding the conditioner with one hand and manipulating the sharpening tool with the other, this tool can be roughened or 50 serrated by frictional engagement of the inner surfaces of the section upon the outer surface of the tool. The conditioner can be rotated or oscillated upon the sharpening tool as well as passing the tool frictionally through it in an axial 55

direction for the purpose of roughening or upsetting the tool surface in more than one direction.

The conditioner 10 can also be employed as a sharpener, and in this connection the cutting edge 32 of a knife 33 can be inserted in either crevice 20 and drawn back and forth, or repeatedly drawn in one direction, until the desired sharpness is secured. It is to be understood that the conditioner can be anchored while the conditioning or sharpening operations are being accomplished, or the conditioner can be held in the hand of the operator and pressure applied manually in the degree desired.

15 By first sharpening or conditioning the edge of a knife in the manner illustrated in Fig. 4, and then using the sharpener 30 to finish or refine the sharpening of the knife, a very satisfactory method of sharpening is made available by this invention.

Although only one form of the invention has been shown and described in detail, it will be apparent to those skilled in the art that the invention is not so limited, but that various changes can be made therein without departing from the spirit of the invention or from the scope of the appended claims.

I claim:

1. A device for conditioning blade sharpeners comprising a plurality of oblong contiguous segments recessed longitudinally in their opposed faces to form a longitudinal opening therethrough, projections and openings being formed on the opposed faces of the segments and normally engaged in loosely interfitting relation to maintain the segments against relative longitudinal movement, resilient means constituting the sole support for said segments and

yieldably maintaining the segments in opposed assembled relation, the surfaces of the segments defining the opening being composed of abrasive material for upsetting the surface of a sharpening tool frictionally forced through the 5

2. A device for conditioning blade sharpeners comprising a plurality of segments of abrasive material recessed to form an opening surrounded by the segments and passing therethrough, resilient means for yieldably maintaining the segments in assembled relation, the surfaces of the abrasive material defining the opening being formed to embrace a metal sharpening tool and to upset the surface of the latter upon forcing 10 it through the opening, opposed segment portions adjacent the extremities of the segments having converging beveled surfaces for receiving and sharpening a knife blade.

3. A device for conditioning a blade sharpener 20 comprising a plurality of oblong contiguous segments recessed longitudinally in their opposed faces to form a longitudinal opening through the device, adjacent portions of adjacent segments being beveled to form V-shaped crevices, a resilient split ring circumferentially engaging the assembled segments and having a projection disposed in one of the crevices to prevent circumferential shifting of the ring, the split portion of the ring being disposed adjacent another one 30 of the crevices to facilitate removal of the ring from the segments, the surfaces of the segments defining the openings being composed of abrasive material for upsetting the surface of a sharpening tool upon frictionally forcing the tool 35 through said opening.

ROBERT T. McDONALD.
